INVENTOR.

George J. Pike

BY

Cyrus W. Rice
his ATTORNEY

UNITED STATES PATENT OFFICE.

GEORGE J. PIKE, OF GRAND RAPIDS, MICHIGAN, ASSIGNOR TO THE W. H. GUNLOCKE CHAIR CO., A CORPORATION OF NEW YORK.

CHAIR.

1,256,726.

Specification of Letters Patent. Patented Feb. 19, 1918.

Application filed April 2, 1917. Serial No. 159,088.

To all whom it may concern:

Be it known that I, GEORGE J. PIKE, a citizen of the United States, residing at Grand Rapids, in the county of Kent and State 5 of Michigan, have invented new and useful Improvements in Chairs, of which the following is a specification.

The present invention relates to chairs, and its object is to provide an improved 10 chair back which shall be strong and which may be readily and economically manufactured, and also to provide an improved method for making chair backs.

This object is attained by the structure and 15 process hereinafter described, such structure being illustrated in preferable form by the accompanying drawings, in which:—

Figure 1 is a side view of a chair;

Fig. 2 is a view in perspective of the 20 upper member of the chair's back;

Fig. 3 is a like view of the same after its lower edge has been cut away;

Fig. 4 is a like view of the lower member of the chair's back;

Fig. 5 is a like view of the same after 25 its upper edge has been cut away; and,

Fig. 6 is a vertical central section of the chair's back.

The chair 1, having the seat 2 and pedestal 30 3, is provided with my chair back 4, whose extremities, in the construction shown, extend on either side to form the arms 5. This back may be supported on the seat, as in the construction illustrated, 35 by the "stumps"—one appearing at 6—and by suitable rods or spindles, as that shown at 7.

The chair back is made in the following manner: Two members, being an upper 40 member 8 and a lower member 9, are fashioned in arcuate form as shown in Figs. 2 and 4, as by steaming and bending wooden strips which may be of uniform width and thickness. The lower edge of the upper 45 member and the upper edge of the lower member are cut away so that the portion removed from each member decreases from a maximum depth at the middle of said member toward its extremities. The line 50 of such cutting away as to the upper member 8 is shown in dotted lines 10 in Fig. 2, said member after being so cut being illustrated in Fig. 3; while the line of cutting as to the lower member is shown in dotted

lines 11 in Fig. 4, said member after being 55 so cut being illustrated in Fig. 5.

The members thus prepared are securely joined together, the lower edge of the upper member to the upper edge of the lower member, as by gluing and by the dowels 12 60 and screws 13, all as illustrated in Fig. 1. This done, the concave surface of the united members is preferably dressed or trimmed down to the dotted line 14 in Fig. 6 along and adjacent to their meeting line, so as to 65 remove the angle formed at said line and provide a smooth inner surface of the chair back. The united members may be trimmed into a desired contour, as shown at the upper edge 15 of the chair back in Fig. 1. 70 It will be seen that this construction of the chair back with its chair arm extensions lends itself readily to the positioning of the middle or rear portion at a higher level above the seat than the extremities 75 or arm portions thereof, as shown in Fig. 1.

The invention being intended to be pointed out by the claims, is not to be limited to or by details of construction 80 shown or described.

I claim:

1. The method of making a chair back which consists in forming two arcuate members, then cutting away those edges of the members which are to be joined together 85 so that each cut-away portion decreases from a maximum depth at the middle of the member from which it is cut toward its extremities, and then joining the upper edge of the lower member and the lower edge 90 of the upper member securely together.

2. The method of making a chair back which consists in forming two arcuate members, then cutting away those edges of the members which are to be joined together so 95 that each cut-away portion decreases from a maximum depth at the middle of the member from which it is cut toward its extremities, then joining the upper edge of the lower member and the lower edge of 100 the upper member securely together, and then trimming down the concave surface of the united members at and adjacent to their meeting line.

3. A chair back comprising two arcuate 105 members securely joined together at their edges, the meeting edges having been cut away so that each cut-away portion de-

creases from a maximum depth at the middle of the member from which it is cut toward its extremities.

4. A chair back comprising two arcuate members securely joined together at their edges, the meeting edges having been cut away so that each cut-away portion decreases from a maximum depth at the mid-

dle of the member from which it is cut toward its extremities, and the concave surface of the united members being trimmed down at and adjacent to their meeting line. 10

In testimony whereof I have hereunto set my hand.

GEORGE J. PIKE.
